UNITED STATES PATENT OFFICE.

JOHN C. WANDS, OF ST. LOUIS, MISSOURI.

CAR-BOLSTER.

SPECIFICATION forming part of Letters Patent No. 558,446, dated April 14, 1896.

Application filed January 7, 1896. Serial No. 574,658. (No model.)

To all whom it may concern:

Be it known that I, JOHN C. WANDS, of the city of St. Louis, State of Missouri, have invented certain new and useful Improvements 5 in Car-Bolsters, of which the following is a full, clear, and exact description, reference being had to the accompanying drawings, forming a part hereof.

My invention relates to an improved car- 10 bolster; and it consists in the novel construction, combination, and arrangement of parts hereinafter described and claimed.

In the drawings, Figure 1 is a side elevation of my improved car-bolster. Fig. 2 is a 15 vertical sectional view taken approximately on the indicated line 2 2 of Fig. 1. Fig. 3 is a view in perspective of one of the cast metal boxes that is located upon the end of my improved bolster. Fig. 4 is a view in perspective of one of the gibbs made use of upon the ends of the boxes of my improved bolster. Fig. 5 is a view in perspective of a spreading-bar. Fig. 6 is a longitudinal sectional view 20 taken approximately through the center of one end of my improved bolster. Fig. 7 is a transverse sectional view taken approximately on the indicated line 7 7 of Fig. 6. Fig. 8 is a view in perspective of the end of a bolster in which truss-rods having solid heads 25 are made use of.

Referring by numerals to the accompanying drawings, 1 indicates a channel-bar, the same being of suitable dimensions and forming the main portion or body of my improved 30 bolster. Located upon the under side of each end of this channel-bar is a rectangular metallic box or housing 2, with each side of which is formed integral the vertically-extending parallel column-guides 3. Extending longitudinally between the outer and inner walls of the boxes are integral webs or 35 strengthening-walls 4, said webs being slightly less in height than are the side and front walls of the box, and formed integral with said webs are laterally-extending strengthening-ribs 5. Between each of these webs 4 and between said webs and the side walls of the box 2 in the top edge of the front wall of said box are formed U-shaped notches or seats 6, 40 which receive the ends of the truss-rods yet to be described.

Formed in the inner wall of the box between

each of the webs and the side walls and the webs are U-shaped notches or seats 7, similar in width to the notches 6, but said notches 55 7 extend nearly to the bottom of the box. Formed integral with the inner faces of the side walls of the box at equal distances apart are vertically-extending parallel ribs 8, with the upper ends of which are formed integral 60 vertically-extending lugs 9. When the boxes are in proper position upon the ends of the channel-bar 1, the lower edges of the flanges of said channel-bar rest directly upon the tops of the ribs 8 and between the lugs 9 and the 65 inner faces of the side walls of said boxes.

Formed integral with the top edges of the sides of the boxes adjacent their rear ends are lugs 10, which, when the boxes are properly positioned upon the ends of the channel-bar, are bent downwardly onto the top surface of said channel-bar, thus securely holding said boxes in rigid position upon said bar. Formed integral with the under side of 70 each of the boxes 2 are annular flanges 11, 75 which perform the function of spring-seats.

Formed integral with the outer ends of the boxes 2 are vertically-arranged ribs 12, said ribs forming a support for the gibbs of which I make use in my improved bolster. These 80 gibbs (indicated by the numeral 13) consist of metallic blocks wedge-shaped in cross-section and equal in length to the width of the box 2. Said gibbs are constructed on their upper ends with laterally-projecting flanges 14, which extend over the top edges of the outer ends of the box and onto the tops of the extreme ends of the channel-bar 1. Formed integral with the outer face of each gib are lugs 15, through which pass inclined apertures 16, the same 85 passing also through the bodies of the gibbs.

17 17 indicate the truss-rods of my improved bolster, there being, preferably, three of said rods, the ends of said rods, when in proper position, passing upwardly through the U-shaped notches or seats 7, formed in the inner ends of the box 2, through the U-shaped seats or notches 6, formed in the outer ends of said box, and through the apertures 16 in the gibbs, which are located on the outer faces 90 of said boxes above the integral ribs 12. In the preferred construction of my improved bolster these truss-rods are provided with integral heads 18 on one end. The opposite

ends of these truss-rods are screw-threaded and nuts 19 are located upon said screw-threaded ends.

Cast-metal saddles 20 are constructed to be located between the truss-rods and the channel-bar 1, there being seats 21 formed in the lower edges of said saddles for the reception of the truss-rods, and lugs 22 are formed integral with the sides of said saddles, the same 10 engaging outside the lower edges of the flanges of the channel-bar 1.

23 indicates a spreading-bar, in the center of which is formed a boss 24, there being a vertical aperture 25 formed through said boss, 15 through which aperture passes the center pin that extends downwardly from the center bearing. The ends of the spreading-bar 23 pass through suitably-formed apertures 26 in the saddles 20, and after these saddles have 20 been properly positioned between the truss-rod 17 and the channel-bar 1 slits 27 are formed in the vertical flanges of said spreading-bar, and the material adjacent these slits and just inside the saddles is upset or bent 25 laterally in order that the correct position of said saddles may be at all times maintained. Where both ends of the truss-rod are provided with solid heads, I make use of a split 30 gib 28, and when this form is used the flange 14 of said gib is dispensed with and lugs 29 are formed integral with the upper edge of the outer end of the box 2, the outer pair of these lugs being bent over the top edge of the split gib 28, while the inner pair of said lugs 35 are bent over the end of the channel-bar 1. (See Fig. 8.)

A bolster of my improved construction may be very cheaply manufactured, is easily assembled and dissembled, is comparatively 40 light in weight, will sustain great weight, and can be, when desired, drawn or returned to its original and proper position should it become sunken down or depressed after long usage.

It is preferred that one of the truss-rods be 45 turned end for end in order that one of the nuts 19 will be located upon the same end with two of the integral heads 18.

By tightening the nuts on the ends of the truss-rods the center of the channel-bar can 50 be elevated and sustained in a plane above the ends of said channel-bar, this being necessary should the center of the bolster be depressed or lowered, resulting from an accident or by overloading the car.

55 I claim—

1. A car-bolster, constructed with a channel-bar, boxes located upon its ends, column-guides formed integral with the sides of said boxes, in which boxes are formed suitable 60 seats, truss-rods arranged beneath the channel-bar, the ends of which truss-rods pass through the seats in the boxes, two saddles interposed between the truss-rods and the

channel-bar and located a distance apart, and means for retaining said saddles in their position. 65

2. A car-bolster, constructed with a channel-bar, boxes located upon its ends, column-guides formed integral with the sides of said boxes, in the outer and inner end walls of 70 which boxes are formed suitable U-shaped notches or seats, truss-rods arranged beneath the channel-bar, the ends of which truss-rods pass through the U-shaped seats in the boxes, saddles interposed between the truss-rods and the channel-bar, a spreading-bar for retaining said saddles in position, gibs located upon the ends of the boxes through which the truss-rods pass, heads formed integral with the truss-rods at one end, and nuts located upon 80 the opposite ends of said truss-rods.

3. In a car-bolster, the combination of the channel-bar 1, truss-rods 17, and metallic boxes located upon the ends of said channel-bar, which boxes are constructed with integral column-guides on their outside faces, integral walls extending longitudinally within said boxes, ribs formed integral with the inner faces of the sides of said boxes on which the flanges of the channel-bar rest, and lugs 90 formed integral with the upper ends of said ribs, the outer and inner walls of said boxes being constructed with U-shaped notches or seats through which the ends of the truss-rods pass. 95

4. In a car-bolster, the combination of a channel-bar 1, truss-rods 17 arranged beneath said channel-bar, boxes located upon the ends of said channel-bar, gibs arranged on the ends of the boxes through which the ends of the 100 truss-rods pass, saddles interposed between the truss-rods and channel-bar, which saddles are provided with integral lugs engaging the lower edges of the flanges on the channel-bar and provided in their lower edges with seats 105 for the truss-rods, and a spreading-bar 23 passing through seats formed in the saddles, portions of which spreading-bar are upset to correctly position the saddles.

5. A car-bolster, constructed with a channel-bar 1, truss-rods arranged beneath said channel-bar, metallic boxes located upon the ends of said channel-bar through which the truss-rods pass, lugs formed integral with the top edges of said boxes, the same engaging 110 upon the top of the channel-bar, gibs located upon the ends of the boxes through which the ends of the truss-rods pass, which gibs are constructed with integral flanges that engage over the ends of the channel-bar. 115

In testimony whereof I affix my signature in presence of two witnesses.

JOHN C. WANDS.
